US00D908487S

(12) **United States Design Patent** (10) Patent No.: **US D908,487 S**
(45) Date of Patent: **** Jan. 26, 2021**

(54) **BOTTLE LID**

(71) Applicant: **ZHEJIANG FEIJIAN TECHNOLOGY CO., LTD.**, Jinhua (CN)

(72) Inventors: **Feijian Xia**, Yongkang (CN); **Chenhan Ouyang**, Anqing (CN); **Zhibo Xiao**, Shaoyang (CN)

(73) Assignee: **ZHEJIANG FEIJIAN TECHNOLOGY CO., LTD.**, Jinhua (CN)

(**) Term: **15 Years**

(21) Appl. No.: **29/741,331**

(22) Filed: **Jul. 11, 2020**

(51) LOC (13) Cl. **09-01**

(52) U.S. Cl.

USPC **D9/439; D7/396.2**

Primary Examiner — Catherine S Posthauer

(57) **CLAIM**

The ornamental design for a bottle lid, as shown and described.

DESCRIPTION

FIG. 1 is a perspective view of a bottle lid showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the bottle lid that form no part of the claimed design.

1 Claim, 8 Drawing Sheets
